US00D768084S

(12) **United States Design Patent** (10) **Patent No.:** **US D768,084 S**
Rodriguez et al. (45) **Date of Patent:** **** Oct. 4, 2016**

(54) **POWER/DATA CONNECTOR**

(71) Applicant: **Google Inc.**, Mountain View, CA (US)

(72) Inventors: **Adam Rodriguez**, San Francisco, CA (US); **Joshua Boilard**, San Francisco, CA (US); **Lawrence Lam**, San Jose, CA (US); **Jeffrey Hayashida**, San Francisco, CA (US)

(73) Assignee: **Google Inc.**, Mountain View, CA (US)

(**) Term: **15 Years**

(21) Appl. No.: **29/531,824**

(22) Filed: **Jun. 30, 2015**

Related U.S. Application Data

(63) Continuation of application No. 29/479,977, filed on Jan. 22, 2014, now Pat. No. Des. 744,428.

CLAIM

The ornamental design for a power/data connector, as shown and described.

DESCRIPTION

FIG. 1 is a perspective view of a power/data connector showing our new design;

FIG. 2 is a front elevation view thereof;

FIG. 3 is a back elevation view thereof;

FIG. 4 is a left side elevation view thereof, the right side elevation view being a mirror image of the left side elevation view; and,

FIG. 5 is a top plan view thereof, the bottom plan view being a mirror image of the top elevation view.

The broken line in the figure drawings is included to show unclaimed environment only and forms no part of the claimed design.

1 Claim, 3 Drawing Sheets
